(57) **CLAIM**

The ornamental design for a headphone, as shown and described.

DESCRIPTION

FIG. 1 is a perspective view of a headphone showing the new design;

FIG. 2 is a front view of the headphone shown in FIG. 1; FIG. 3 is a back view of the headphone shown in FIG. 1; FIG. 4 is a left side view of the headphone shown in FIG. 1; FIG. 5 is a right side view of the headphone shown in FIG. 1;

FIG. 6 is top view of the headphone shown in FIG. 1; and, FIG. 7 is bottom view of the headphone shown in FIG. 1. The broken lines in the drawing illustrate portions of the headphone that form no part of the claimed design.

1 Claim, 5 Drawing Sheets
